JAMES GRIEVE, OF DODGE CITY, KANSAS, ASSIGNOR OF ONE-HALF TO
CLYDE BELLISOR McCLURE, OF DODGE CITY, KANSAS.

BLADE-CLAMP FOR SAW-FRAMES.

No. 800,099.

Specification of Letters Patent.

Patented Sept. 19, 1905.

Application filed January 25, 1905. Serial No. 242,614.

To all whom it may concern:

Be it known that I, JAMES GRIEVE, a citizen of the United States, and a resident of Dodge City, in the county of Ford and State of Kansas, have invented a new and Improved Blade-Clamp for Saw-Frames, of which the following is a full, clear, and exact description.

Ordinarily the frame of a hacksaw or other saw-frame of a like character is furnished with two clamps for gripping the ends of a saw-blade, so that the blade when rendered taut will be adapted for service. The clamps usually employed each consist of a jaw fixed upon a member of a saw-frame that is mated with a loose jaw that is clamped upon the fixed jaw by means of set-screws which require the use either of a screw-driver or a pair of pliers for turning them, and thus force the loose jaws upon the ends of the saw-blade that have been introduced between respective clamps.

The object of my invention is to provide a novel, simple, and inexpensive clamping attachment for each of the ordinary blade-clamps on a saw-frame which affords convenient means for reliably securing the ends of a saw-blade in clamped condition thereon and that may be quickly and readily adjusted for clamping or releasing the saw-blade without requiring the use of pliers or any other implement to effect such an adjustment of the improved attachment.

The invention consists in the novel construction and combination of parts, as is hereinafter described, and defined in the claims.

Reference is to be had to the accompanying drawings, forming a part of this specification, in which similar characters of reference indicate corresponding parts in all the figures.

Figure 1 is a side view of a hacksaw having the improvement mounted upon the ordinary clamping means for detachably securing a saw-blade by its ends on the frame. Fig. 2 is an enlarged plan view of an ordinary clamp on a hacksaw and of the improvement mounted thereon, the ordinary clamping device and the improved attachment being clamped upon an end portion of a saw-blade. Fig. 3 is a plan view of the same, but showing the clamp and the improved attachment adjusted for the introduction of an end of a saw-blade. Fig. 4 is a longitudinal sectional view of details substantially on the line 4-4 in Fig. 2, showing the improved attachment engaged with an end of a saw-blade. Fig. 5 is a detached perspective view of the improved saw-blade clamp after it is bent for service, and Fig. 6 is a perspective view of the improved clamp before a limb thereon is bent into hook form.

The improvement hereinafter described is designed for use on any kind of frame whereon a saw-blade is to be held in a taut condition, the drawings showing one form of saw-frame upon which it may be applied.

The saw shown in Fig. 1 is of a kind employed for cutting metal, and consists, essentially, of a back bar 6, that is curved near one end, as at 6^a, and terminates in a fixed jaw 7. The opposite end portion of the back bar is held to slide neatly in the transversely-perforated head 8^a on one end of a post 8, and in said head is a set-screw 9, that by adjustment will secure the bar in the head at any point of sliding movement. A fixed jaw 10 is formed on the remaining end of the post 8, and from said jaw at its outer end extends a grip-piece 7^b or handle 11, and, as shown in Fig. 1, the fixed jaws 7 and 10 are disposed in the same longitudinal plane. The jaws 7 and 10 are substantially alike, consisting of flat elongated blocks, the similar sides of which that a saw-blade usually has contact with being alined.

Upon the fixed jaws 7 and 10 are respectively mounted the loose jaws 7^a 10^a, the means for adjustably holding these clamping-jaws opposite the clamping-faces on the fixed jaws consisting of the similar set-screws 7^b 10^b, which are inserted loosely through a perforation formed transversely in a respective loose jaw near one end of the same. There is a threaded perforation formed in each fixed jaw 7 10 opposite the one in a respective loose jaw, and in these threaded perforations are screwed end portions of the set-screws 7^b 10^b, whereby the loose clamping-jaws are adjustably connected near one end of each corresponding fixed jaw. It is to be understood, however, that in some cases the set-screw 10^b may be dispensed with. At a suitable distance from the set-screws 7^b 10^b a perforation is formed in each loose jaw 7^a 10^a, and in each corresponding fixed jaw 7 10 a threaded perforation is formed opposite said perforations in the loose jaws. A thumb-screw 12 is inserted loosely through the perforation in the loose jaw 7^a, preferably having a winged head 12^a, said thumb-screw screwing into the threaded perforation that is opposite its threaded end in the fixed jaw 7. A similar

thumb-screw 13 is passed through the perforation in the loose jaw 10^a and is screwed into a threaded perforation formed opposite it in the fixed jaw 10.

5 The hacksaw-frame and clamping means hereinbefore described is such as is usually employed for holding a saw-blade stretched between the clamping-jaws for service and is shown to clearly represent the application 10 of the improvement, which corrects the following defect in an ordinary hacksaw or other saw frame. It has been found necessary in order to reliably secure the ends of a saw-blade between the fixed jaws and loose 15 jaws on the saw-frame that a screw-driver must be used for adjusting the set-screws 7^b 10^b and then a pair of pliers or a hand-vise be employed to further tighten the winged thumb-screws 12 13 after they have been set 20 up as tightly as possible with the thumb and fingers.

The improved attachment which will now be described enables the secure clamping of the ends of a thin saw-blade to be effected 25 quickly without using an implement other than the hands of a person who is adjusting the blade to place on the saw-frame.

As clearly shown in Fig. 5, the improved 30 clamping attachment for each jaw on a hacksaw-frame consists, preferably, of a strip of plate metal that is resilient, said strip being curved edgewise between its ends, so as to give it semicircular form, this portion 14 of the clamping device having an equal thickness 35 throughout its body. One end portion of the metal strip projects tangentially from the semicircular part 14 and is thickened somewhat, but parallel on the upper and lower sides, affording a pressure-arm 14^a, that inclines flatwise from the portion 14, so that when the latter is seated upon a level surface the arm will be inclined upwardly therefrom. The thickened portion 14^a is marginally rectangular and has its three free edges *a* beveled 40 downward and outward, as is shown in Fig. 5. The concave inner edge of the semicircular member 14 is continued toward the arm 14^a, terminating in an end wall *b*, that is substantially parallel with the adjacent side edge 45 *a* of the arm 14^a. A foot member 14^b, which may be rectangular on the edges, is formed on the remaining end of the semicircular portion 14 and has the end wall *b* as one of its edges. An upright limb 14^c is formed on 50 the outer side edge of the foot 14^b, and upon its free end a portion 14^d is bent laterally, forming a hook member that projects above the foot and semicircular part 14, this bending being usually effected when the device is 55 placed in position for service.

To apply the improvement for use, each one of the pair provided is strung upon the body of a respective thumb-screw 12 13, and the limb thereon engages the normally lower

edge of a respective fixed jaw 7 10, the 65 thumb-screw holding the device in position after the hook members 14^d of the limb 14^c are engaged with a side of the fixed jaw toward which the limb projects. It will be seen that the resilient arm 14^c on each of the improved 70 clamping devices will press upon the adjacent side of a respective loose jaw 7^a 10^a and force the same away from the corresponding fixed jaw when the thumb-screw that engages the loose jaw is relaxed. If both of the loose 75 jaws 7^a 10^a are permitted to assume the inclined positions shown for one loose jaw in Fig. 3 and the set-screws 7^b 10^b have been properly adjusted to serve as fulcrums and 80 coact with the thumb-screws 12 13 for compressing the loose jaws toward the fixed jaws, it will be seen that when the end portions of the saw-blade 15 are respectively introduced 85 between the foot 14^b and arm 14^a on each clamping device and the thumb-screws 12 13 are screwed for compression of the loose jaws 7^a 10^a this will force the resilient arms 14^c toward the fixed jaws 7 10 and kink the saw-blade 15 near each of its ends, thus producing 90 offset shoulders *c* thereon, which will prevent 95 the end portions of the saw-blade from sliding in the clamps. It will be seen that as the hook members 14^c 14^d are bent so as to hook 100 upon the fixed jaws 7 or 10 said hook will hold the improved clamp in position. It will 105 be evident that the degree of compression necessary to kink the saw-blade laterally near each end of the same can be effected with ease, and as the edges on the foot and 110 arm members of the improved clamps are beveled slightly the shoulders on the blade will be so shaped as to avoid breaking the 115 blade, it being customary to anneal the end portions of blades for hacksaws to prevent them from breaking.

To strain a saw-blade and render it taut after the ends thereof are clamped upon the frame as stated, the screw 9 is first slackened, then the bar 6 is slid in the head 8^a, so as to stretch the blade, and then the screw is tightened, and, as before explained, the saw-blade 120 may be rendered taut for effective service without danger of breaking it where it is clamped upon the jaws of the frame.

Having thus described my invention, I claim 115 as new and desire to secure by Letters Patent—

1. A clamp for holding the ends of a saw-blade clamped upon a saw-frame, comprising a strip of metal curved edgewise to produce a substantially open ring, one end portion forming a flat foot having a limb thereon, and the other affording an arm that inclines above the plane of the foot.

2. A clamp for holding the ends of a saw-blade clamped upon a saw-frame, comprising 125 a strip of plate metal curved edgewise between its ends, forming a substantially open ring, one end of said strip projecting tangen-

tially from the curved portion, forming an arm that inclines upward from the plane of the curved portion, the other end of said strip affording a foot-rest having an upright limb 5 thereon which may be bent to terminate in a lateral hook.

3. A clamp for holding the ends of a saw-blade clamped upon a saw-frame, comprising a strip of resilient plate metal curved edge-wise between its ends into open-ring form, an arm extended tangentially from one end of the curved member and thickened to produce a seat for the end portion of a saw-blade, and beveled on the edge that engages with said 15 saw-blade, a foot-piece extended from the remaining end of the curved portion and having an edge spaced from and parallel with an adjacent edge on the arm, a limb projected up from the foot-piece at its outer edge, 20 which is normally straight but may be bent to form a hook on the upper end of said limb

that is extended toward the curved portion of the clamp.

4. The combination with a saw-frame having a fixed jaw thereon, a loose jaw, and adjusting-screws for holding the loose jaw on the fixed jaw, of a clamping means, comprising a resilient metallic strip bent edgewise into nearly ring form, an arm on one end of the curved member, extended tangentially 25 therefrom, a foot on the other end thereof, the arm inclining up toward its end above the plane of the foot, a limb extended upward from an edge of the foot, and a hook member formed upon the free end of the limb. 30 35

In testimony whereof I have signed my name to this specification in the presence of two subscribing witnesses.

JAMES GRIEVE.
